CLAIM

The ornamental design for a bag, as shown and described.

DESCRIPTION

FIG. 1 is a rear perspective view of a bag showing my new design;

FIG. 2 is a rear view thereof; and,

FIG. 3 is another rear perspective view thereof.

The even-length broken lines within the shaded area represent stitching that forms no part of the claimed design. The broken lines immediately adjacent to the shaded area define the bounds of the claimed design and form no part thereof. The uneven-length broken lines depicting the remainder of the bag form no part of the claimed design.
